UNITED STATES PATENT OFFICE

ZIGMAN CHAPLICK, OF CHICAGO, ILLINOIS

DESIGN FOR A TOP FOR SMOKING STANDS

Application filed March 21, 1931. Serial No. 39,197. Term of patent 7 years.

To all whom it may concern:

Be it known that I, ZIGMAN CHAPLICK, a citizen of the United States, residing at 732 Mather Street, Chicago, Illinois, have invented a new, original, and ornamental Design for a Top for Smoking Stands, of which the following is a specification, reference being had to the accompanying drawings, forming part thereof.

In the drawings:

Fig. 1 is a plan view,
Fig. 2 is a front elevational view, and
Fig. 3 is a side view of my design.

I claim:

The ornamental design for a top for smoking stands as shown.

ZIGMAN CHAPLICK.
